SWITCH OPERATOR

Clarence W. Tydeman, Redwood City, Calif.

Application September 14, 1955, Serial No. 534,285

4 Claims. (Cl. 200—47)

This invention relates to improvements in electric switching mechanisms and has reference more particularly to a switch operator for controlling the operation of automatic machines of the general type to which applicant's pending application Serial No. 324,805, filed December 8, 1952, now abandoned, relates.

Machines of this general type employ hydraulic rams for advancing cutting tools such as boring bars and employ hydraulic fluid under high pressure for operating the rams. The speed at which the tool advances must be accurately controlled for which purpose magnetically operable valves are provided which are operated by the machine at preset intervals to change its speed or effect other changes. Such machines are carefully adjusted and preset to perform the desired machine operation and employ for this purpose electromagnetic valves, relays, micro-switches and switch operators that function cooperatively to effect the different changes in the cycle of the machine operation. The present invention relates to a switch operator that can be readily adjusted and positively secured in adjusted position.

Having thus described in a general way the purpose of the invention, it will now be described in greater detail for which purpose reference will be had to the accompanying drawing, in which:

Figure 1 is a diagrammatic representation of a quill type boring machine in connection with which the present invention has been shown;

Figure 2 is a side elevational view of the switch operator showing its relation to an electric switch;

Figure 3 is an end elevation of the operator to an enlarged scale, looking in the direction of arrow 3 in Figure 2;

Figure 4 shows a development of the outer surface of the operator; and,

Figure 5 is a section taken on line 5—5 Figure 2.

Referring now to the drawing, reference numeral 10 designates the switch operator to which this invention specifically relates, in operative relation to an electric switch 11 from the top of which a switch handle 12 projects. Although the invention has a broader application or use than the one illustrated in Figure 1, it will be described in connection with the boring machine as illustrating one use that is typical.

In Figure 1 reference numeral 13 designates the cylinder of a hydraulic ram through which the tubular piston rod 14 extends. Attached to the piston rod is an annular piston 15 that forms the subject of a separate application. Journalized in the piston rod is a boring bar 16 provided at its end with a cutting tool 17. Attached to the left-hand end of the piston rod, when viewed as in Figure 1, is an arm 18, whose upper end is provided with a plate 19 that serves as a support for motor 20. Means, which is represented by a rod 21 that is attached at its outer end to arm 18 and has a slidable connection with guide 22, serves to prevent arm 18 from turning when the machine operates. Associated with the parts described is a

supply of hydraulic fluid contained in sump 23 and a power driven gear pump 24 whose intake port is connected with the sump by pipe 25 and whose delivery port is connected with the cylinder as shown. The other 5 end of the cylinder (right end) is provided with an outlet pipe 26, the outlet of which is controlled by a needle valve 27. Extending from pipe 26 is a pipe 28 that communicates with the sump and in which is positioned a normally closed valve 29 of the plunger type illustrated 10 in the application above identified, which is operable by means of a solenoid 30. The switch 11 is normally open and is connected with the solenoid by means of a circuit 31 in which is a battery 32. When switch 11 closes valve 29 opens and provides a by-pass about valve 27 to effect quick traverse of the tool. When switch 11 opens the tool will resume its slow motion.

As stated above the use illustrated and described is merely for the purpose of illustration. It is to be understood, of course, that the invention is not limited to any 20 particular use.

Referring now to Figures 2, 3 and 4, it will be seen that the switch operator 10 is provided with a cam whose edge 33 extends a short distance beyond the surface of the heel portion 34 and, as illustrated, makes slightly less 25 than one complete turn leaving a gap 35 as shown in Figure 3. Figure 4 is a development of the outer surface of member 10. The operator or cam 10 is provided with a cylindrical shank 36 that fits snugly in an opening in the lower end of arm 18 and is held in place by washer 37 and cap screw 38. In the drawing the switch 11 is normally held in open position and is closed by a downward push on button 12. In the drawing, button 12 is urged against surface 34 by the spring that keeps the switch contacts separated. When operator 10 has moved to 30 towards the right until point 39 of the cam reaches button 12, further movement of member 10 will depress button 12 and close the switch. In some cases switch 11 is normally closed and is then opened by the cam. The extent of the longitudinal movement of member 10 before the switch is operated depends on the rotary position of the cam relative to the button 12 and in setting up the machine for a certain job the mechanic loosens the cap screw 38 and rotates the cam until it will engage and operate the switch when the parts reach a predetermined 35 position. When the cam has been properly adjusted, screw 38 is tightened to hold it securely in place. This arrangement allows the parts to be adjusted with great accuracy and speed.

In the drawing switch 11 has been shown directly 50 underneath cam 10 but it is obvious that it may occupy any rotary position relative to the cam. When switch 11 is a micro-switch circuit 31 is normally provided with a relay in the usual manner.

What is claimed as new is:

- 55 1. A switching mechanism comprising in combination, a base, an electric switch having an upwardly extending switch handle, attached to the base, an elongated substantially cylindrical switch operator cam member operatively attached to the base, positioned above the switch handle 60 and mounted for both axial and rotary movement relative to the switch handle, said operator cam member having a cam surface spiraled about its outer surface, the cam surface making not to exceed one complete turn, the parts being so positioned and arranged that the cam 65 surface will engage the switch handle and operate the switch when the cam member moves axially, the point of switch operation relative to the axial movement of the cam surface being dependent on the rotary position of the cam member relative to the switch handle.

- 70 2. An adjustable switching mechanism, in combination, a base, a switch attached to the base, said switch having

a switch handle projecting upwardly therefrom, an elongated, substantially cylindrical switch operating cam member supported by the base and positioned above the switch handle, means for moving said cam member in an axial direction, a cam surface spiraled about the switch operator in a position facing the switch handle, the cam member being mounted for rotary adjustment relative to the switch handle, whereby the distance from the cam surface to the switch handle in any axial position of said cam can be changed by turning the cam member about its axis.

3. A mechanism in accordance with claim 2 in which the switch operator cam member has an outer surface comprising a heel portion of one radius and a raised cam

surface of a larger radius the edge of the raised portion which forms a cam surface extending spirally about the operator.

4. A mechanism in accordance with claim 3 in which the raised helical cam surface forms less than one complete turn about the heel portion.
